Primary Examiner — Paula Allen Greene

(74) Attorney, Agent, or Firm — Wood Herron & Evans LLP

(57) **CLAIM**

The ornamental design for an urn pedestal for funeral vehicle as shown and described.

DESCRIPTION

FIG. 1 is a front right perspective view of an urn pedestal for funeral vehicle showing our new design;

FIG. 2 is a front view of the urn pedestal for funeral vehicle of FIG. 1;

FIG. 3 is a left side view thereof;

FIG. 4 is a right side view thereof;

FIG. 5 is a top view thereof; and,

FIG. 6 is a rear view thereof.

The broken and dashed lines depict portions of the urn pedestal for a funeral vehicle that form no part of the claimed design.

1 Claim, 6 Drawing Sheets
